UNITED STATES PATENT OFFICE.

CHARLES H. BRIGDEN, OF WALTHAM, MASSACHUSETTS.

DESIGN FOR A PADLOCK-CASE.

SPECIFICATION forming part of Design No. 28,224, dated February 1, 1898.

Application filed September 21, 1896. Serial No. 606,589. Term of patent 14 years.

To all whom it may concern:

Be it known that I, CHARLES H. BRIGDEN, of Waltham, in the county of Middlesex and State of Massachusetts, have invented a certain new and original Design for a Padlock-Case, of which the following is a specification.

Figure 1 represents a side elevation of my new bicycle-padlock, the hasp being closed or locked. Fig. 2 represents an end view, partly in section, on the line 2 2 of Fig. 1.

The leading or material feature of my design consists in the cylindrical body of the padlock-case and the curved hasp rectangular in cross-section and connected with the cylindrical body close to the ends of the latter.

As shown in the drawings, *a* represents the cylindrical body of the padlock-case, and *b* represents the hasp, which is rectangular in cross-section.

What I claim is—

The design for a padlock-case, substantially as shown and described.

In testimony whereof I have signed my name to this specification, in the presence of two subscribing witnesses, this 11th day of 25 September, A. D. 1896.

CHARLES H. BRIGDEN.

Witnesses:

A. D. HARRISON,
C. F. BROWN.
